(57) **CLAIM**

The ornamental design for a front top cover of vehicles as shown and described.

DESCRIPTION

FIG. 1 is a front view of a front top cover showing my new design.

FIG. 2 is a rear view thereof.

FIG. 3 is a plan view thereof.

FIG. 4 is a bottom view thereof.

FIG. 5 is a right side view thereof.

FIG. 6 is a left side view thereof.

FIG. 7 is a perspective view thereof as seen from the right front side.

FIG. 8 is a perspective view thereof as seen from the left front side.

FIG. 9 is a perspective view thereof as seen from the right rear side.

FIG. 10 is a perspective view thereof as seen from the left rear side; and,

FIG. 11 is a reference view of the front top cover on a reduced scale showing its state of use on a vehicle.

The surface contour of the bottom portion of the subject design is not part of the claimed subject matter. Moreover, the broken lines shown are for illustrative purposes only and form no part of the claimed design.
